UNITED STATES PATENT OFFICE

JOHN J. FARRELL, OF VILLANOVA, PENNSYLVANIA

GARMENT SUPPORTER

Application filed April 21, 1931. Serial No. 531,765.

My invention relates to garment supporters such as are used to support stockings or other articles of underwear and relates particularly to the means for gripping the stocking or other article in which one member lies between the material and the limb of the wearer and the other member lies outside the material and is provided with means for engaging a button or stud shaped projection on the inner member. This button or stud shaped projection is liable to puncture or break the thread of the stocking and the breaking of a thread in a knit stocking tends to start a "run" which is difficult to check and unless checked ruins the stocking. Further the button or stud projects in such a way as to tend to be unsightly and to catch in outer garments and if accidentally struck tends to bruise the limb of the wearer.

It is an object of my invention to overcome these objections by providing a gripping device which will lie flat without any projecting stud, will afford a wide grip on the material and will firmly lock the gripping members together and will be simple and inexpensive in construction.

With the objects above indicated and other objects hereinafter more fully explained in view, my invention consists in the construction and combination of elements hereinafter described and claimed.

Referring to the drawings:

Figure 1 is a central, vertical, sectional view of my garment supporter on an enlarged scale.

Figure 2 is a front view, and Figure 3 is a side view of the complete garment supporter.

Figure 4 is a front view and Figure 5 is a side view of the outer member of the garment supporter.

Figure 6 is a front view and Figure 7 is a side view of the inner member of the garment supporter.

Figure 8 is a detail perspective view of the cushioning device, and

Figure 9 is a top plan view of the upwardly extending tongue 7.

In the drawings 1 and 2 indicate the two members or elements of the garment supporter between which the material of the

stocking or other garment is held, 1 indicating the inner member, that is the member which in use is next to the limb of the wearer and 2 indicating the outer member. The inner member 1 is preferably cut or stamped from sheet metal in the shape shown in Figure 6 having at its upper end a strap opening in slot 3 and, preferably, also a strap opening or slot 4 at its lower end.

Between these strap openings the material of the member is so cut as to leave near the upper strap opening a downwardly depending tongue 5 which is curled upward and forward into a substantially cylindrical roll 6, and to leave above lower strap opening 4 an upwardly extending tongue 7 which is bent over forward and downward into inverted U shape to form one of the gripping members between which the material of the stocking or other garments is held. This tongue is provided at the top of the inverted U with an opening 8, into which a portion of the upper edge of the cushion 12, carrying with it the material of the garment to be supported may enter.

The outer member 2 is provided at its upper end with a slot 9 of such length as may be desired to receive the broad band usually employed to connect the garment supporter to the waist band, corset, or other garment of the wearer. Below this slot 9 is formed a second slot 10 corresponding in length with the upper opening 3 of member 1. The lower end portion 11 of member 2 is curled or bent inward and upward into U shape so as to hold a cushion piece 12 of rubber or like resilient material, the material of this end portion 11 being preferably provided with opening 14 into which the material of the cushion piece 12 may enter to insure its being firmly held.

Between the opening 10 and the lower end of member 2 are formed upper opening 15 and lower opening 16 corresponding in shape to the openings left in member 1 by cutting out the tongues 5 and 7, a bar 17 being left between slot 10 and opening 15.

Inner member 1 is substantially flat from end to end but outer member 2 is so bent that while its upper portion will lie flat against the upper portion of member 1 it is

bent outward at 20 from slightly below bar 17 so as to leave a substantial space between members 1 and 2.

In use the two members are loosely connected by a strap or band of textile material extending through openings 3, 10 and 4. The inner member 1 is placed between the limb and the stocking or other garment to be supported so as to bring its upper edge above the U shaped tongue 7. The outer member 2 is then placed over the inner member so that the cushion 12 lies over tongue 7 which is covered with the material of the stocking. The two members are then pressed together and the outer member is pulled sharply upward thus forcing cushion 12 and the material of the stocking into the inverted U of tongue 7 and bar 17 is lifted over the roll 6 thus locking the parts together and holding the material of the stocking firmly between the cushion 12 and the U shaped tongue 7, the material being forced to some extent into opening 8 of the tongue.

The distance between the top of the inverted U of the tongue 7 and the top of roll 6 is slightly more than the distance between the upper edge of cushion piece 12 and the lower edge of bar 17 so that when the upper portions of the members are pressed together the cushion piece 12 will be compressed and by its resistance will hold the bar locked on roll 6.

The two members 1 and 2 may be made of relatively thin material much thinner than is required for the single metallic member of the garment supporter commonly used.

Having thus described my invention, what I claim is:

1. In a garment supporter a gripping device comprising an outer member, an inner member loosely connected at its upper end to the outer member, the outer member being provided near its lower end with means for holding a cushion and having near its upper end a cross bar, and the inner member being provided near its lower end with an outwardly and downwardly extending tongue adapted to cooperate with the upper end of the cushion to grip the material of the garment to be supported and having near its upper end locking means adapted to engage the underside of the cross bar of the outer member.

2. In a garment supporter a gripping device comprising an outer member, an inner member loosely connected at its upper end to the outer member, the outer member being provided near its lower end with means for holding a cushion and having near its upper end a cross bar, and the inner member being provided near its lower end with an outwardly and downwardly extending tongue adapted to cooperate with the upper end of the cushion to grip the material of the garment to be supported and having near its

upper end locking means adapted to engage the underside of the cross bar of the outer member, the upper edge of the cushion and the cooperating tongue of the inner member being of substantial extent horizontally.

3. In a garment supporter a gripping device comprising an outer member, an inner member loosely connected at its upper end to the outer member, the outer member being provided near its lower end with means for holding a cushion and having near its upper end a cross bar, and the inner member being provided near its lower end with an outwardly and downwardly extending tongue adapted to embrace the upper end of the cushion and having near its upper end an upwardly and outwardly roller tongue adapted to engage the underside of the cross bar of the outer member.

4. In a garment supporter a gripping device comprising an outer member, an inner member loosely connected at its upper end to the outer member, the outer member being provided near its lower end with inwardly and upwardly extending tongue and having near its upper end a cross bar, and the inner member being provided near its lower end with an outwardly and downwardly extending tongue adapted to cooperate with the upwardly and inwardly extending tongue of the outer member to embrace the upper end of the cushion and having near its upper end locking means adapted to engage the underside of the cross bar of the outer member.

5. In a garment supporter a gripping device comprising an outer member, an inner member loosely connected at its upper end to the outer member, the outer member being provided near its lower end with an upwardly extending device adapted to engage the material of the garment to be supported, and having near its end a cross bar, and the inner member being provided near its lower end with an outwardly and downwardly extending tongue adapted to embrace the upper end of the upwardly extending device carried by the outer member and having near its upper end locking means adapted to engage the underside of the cross bar of the outer member.

6. In a garment supporter a gripping device comprising an outer member, an inner member loosely connected at its upper end to the outer member, the outer member being provided near its lower end with means for holding a cushion and the inner member being provided with an outwardly and downwardly extending tongue adapted to embrace the upper end of the cushion and having an opening therein into which the material of the cushion may enter.

In testimony whereof, I hereunto affix my signature.

JOHN J. FARRELL.
